TRIMMING MACHINE

John H. Fridén, East Orange, N. J., assignor to
 The Sun Tube Corporation, Hillside, N. J., a
 corporation of New Jersey

Application March 25, 1933, Serial No. 662,657

18 Claims. (Cl. 29—38)

This invention relates to automatic machinery particularly adapted for the trimming off of the end of a tubular member. The improved machine is especially suited for operation upon relatively thin walled, cylindrical members having a closed bottom and formed of a metal which may become distorted upon the ordinary application of a cutting tool. In this connection a novel cutting method has been developed. It will be understood, however, that various phases of the invention are not limited to this particular use but may be applied to a variety of other situations.

The machine embodies a step by step rotary head having a series of work supporting chucks adapted to be shifted from one to another of a plurality of stations. In one position the articles to be trimmed are automatically and successively fed from a conveyor into the chucks. As the chucks reach another position they are rotated and a suitable trimming tool, capable of providing the article with a finished end, is rendered effective. In a third position the finished articles are automatically discharged. It will be understood that all of the operating parts are so timed and related that upon each step of rotation of the head a work piece will be inserted in one of the chucks, another chuck will be rotated to permit the trimming to be performed and a third chuck will be opened to allow the finished article to be discharged.

It has been a primary object of the invention to provide a simple, efficient and compact machine of the character indicated capable of rapidly performing the trimming operations. The construction disclosed is particularly applicable to the trimming of the ends of extruded or drawn cup-like members formed of a metal such as zinc. This renders the machine especially suited to the trimming of extruded battery cups and the like.

Various other objects and advantages of the invention will be made apparent as an illustrative machine is described in greater detail in conjunction with the accompanying drawings in which:

Fig. 1 is a top plan view of a machine embodying the invention.

Fig. 2 is a side elevation of the machine with a few parts broken away and shown in section.

Fig. 3 is a front elevation of the machine on a larger scale.

Fig. 4 is an enlarged detail, partly in elevation and partly in section, of certain cam actuated linkage for controlling the cutter.

Fig. 5 is an enlarged vertical, transverse section along the line 5—5 of Figure 2.

Fig. 6 is an enlarged top view of one of the chucks in the cutting position.

Fig. 7 is a vertical section through the chuck 5 along the line 7—7 of Figure 6.

Fig. 8 is a detail in section showing the chuck of Figure 7 with its jaws released.

Fig. 9 is an enlarged detail partly in elevation and partly in section along the line 9—9 10 of Figure 4 of the cutter carriage and associated parts, and

Fig. 10 is an enlarged detail showing a portion of Figure 9 with the parts in shifted position.

Referring now to the drawings, particularly 15 Figure 1, the machine embodying the invention comprises a supporting frame 10 having suitable legs 11 for holding the mechanism at an appropriate elevation above the floor. Power for the operation of the machine may be derived from any 20 suitable source. For example a pulley 12 may receive power from a motor or a line shaft through a belt 13. The pulley may be secured to a shaft 14, carried by a bearing bracket 15 secured to the frame, and also journaled in a bearing 16. At an intermediate point a pinion 17 is secured to the shaft and meshes with a large gear 18 secured to a shaft 19. Above the shaft 19 there is located a parallel shaft 20. Suitable connections, preferably a Geneva gearing are provided between the two shafts, the arrangement being such that upon each revolution of the shaft 19 the shaft 20 will be given one step of movement, say a one-quarter turn. This will be accomplished in a corresponding portion of the 35 rotation of shaft 19 and during the balance of the rotation of this shaft the shaft 20 will be held stationary. For this purpose a Geneva roller 21 may be carried by an arm 22 secured to the shaft 19 and may cooperate, in well-known manner, 40 with notches in a Geneva wheel 33 secured to shaft 20. A locking disk 24 carried by shaft 19 serves to prevent overthrow of the Geneva wheel and locks it against turning between the successive steps, in the usual way of a Geneva lock. 45

Adjacent its forward end the shaft 20 carries a large disc or head 25 which supports a plurality of chucks, designated generally as 26 in Figure 5. Four of these chucks are shown although three will be sufficient for the particular 50 purposes of the illustrative machine. It will be apparent that the number and arrangement of the chucks may be varied to suit the particular requirements. Inasmuch as all of the chucks are of similar construction it will be necessary only 55

to describe one of them in detail. Referring to Figures 6 and 7 there is provided a bearing member 27 for each of the chucks having a reduced portion 28 at its end adapted to be passed through an aperture in the disc 25. The bearing member is secured to the disc by means of machine screws 29. Within the bearing member is mounted a chuck supporting spindle or shaft 30. Beyond the forward end of member 27 an enlarged collar portion 31 is provided on the spindle to prevent further inward movement of the spindle. At its inner end the spindle is provided with a detachable end portion 32 secured to the main part by means of a hollow screw 33. For a reason to be explained hereinafter the spindle is provided with a passage 34 from end to end in communication with a passage through the screw 33. Between the end of member 28 and a shoulder on the portion 32 there is mounted a grooved wheel 35 which is secured to the spindle by means of a set screw 36.

Forwardly of the collar 31 there is secured to the spindle a chuck-jaw supporting member 37 having pairs of ears 38 carrying pivot pins 39 for pivotally supporting the jaw members 40. Each jaw may have secured thereto, as by the screws shown, a plate 41. At its inner end each jaw member has pivotally connected thereto a toggle link 42 whose other end is pivotally attached to a slidable member 43 mounted for rotation and axial movement upon the bearing member 27. Member 43 is formed with a groove 44 which receives a roller 45 at the upper end of each of a pair of bifurcated arms 46 that straddle the member. These arms are a part of a bell crank lever pivoted at 47 upon a support 48 secured to the hub of the disc 25 by a screw 49. The bell crank lever has a forwardly extending arm 50 which carries a roller 51 mounted for rotation on the arm by means of a screw 52. A spring 53 mounted over a stud 54 on the disc and over a similar stud 55 on the bell crank tends to rock the bell crank in a clockwise direction, Figure 7. This serves to slide the member 43 forwardly and by the action of the links 42 forces the jaws of the chuck together under spring pressure. In order to separate or disengage the jaws from the work piece the roller 51 cooperates with a cam surface secured, as by means of screws 57, to a portion of the frame 10. As will be made more clear hereinafter the cam surface 56 is so formed as to have a high portion in the path of the roller 51, as the latter is carried around by the head or disc 25, over that portion of the cycle at which the article is to be gripped and a low portion over that part of the cycle at which the article is to be released. Its form is clearly indicated in Figure 5. The closed and open positions of the jaws are indicated in Figures 7 and 8 respectively.

Each jaw member carries a spring pressed gripping element 58. This is slidable in an aperture in the jaw and is urged toward the article to be gripped by means of a spring 59 secured by a screw 60. The end of each plunger element is inclined slightly to the axis of the chuck, as shown in Figure 7, even when the article is gripped. This provides a corner 61 which lightly retains the article even though the jaws are not together but it will not prevent removal of the article under a more positive action. The purpose of this will be made more apparent hereinafter.

We may now consider the means provided for automatically feeding the work pieces successively between the jaws of the chucks. This mecha-

nism is most clearly shown in Figs. 1, 2, and 3. The article upon which the present machine is adapted to operate is an elongated, cup-like element 62, whose form is most clearly indicated in Fig. 8. It may be in the form, for example, of an extruded battery cup having an open mouth with an irregular contour and a flat, closed bottom. The present machine is especially suited for the trimming of the irregular ends of these cups. They may be deposited in any suitable way, either by hand or automatically, from some other machine or conveyor upon a belt 63. At each side of the belt there may be arranged a chain 64 of suitable construction, carrying a series of spaced, upstanding pins 65. The pins on the two chains should be aligned transversely of the belt, as best shown in Fig. 1. On each chain the pins should be suitably spaced to hold the articles an appropriate distance apart and to permit them to be introduced successively at appropriate intervals into the path of certain operating devices. The outer ends of the belt and chains may be suitably supported upon a pulley and sprockets carried by a shaft 66 journaled in a portion of the frame. At their inner ends the chains are carried by a pair of sprockets 67 secured to a shaft 68 while the belt travels around a pulley 69, also secured to this shaft.

Suitable connections are provided for continuously rotating the shaft 68 at an appropriate, relatively slow speed. For this purpose the shaft is connected by a universal joint 70 with a slightly inclined shaft 71, whose opposite end is connected by another universal joint 72 with a short shaft 73 parallel with, but offset from, the shaft 68. A sprocket 74 is secured to the shaft 73 and cooperates with a chain 75 which extends transversely of the machine and is supported at its opposite end by means of a sprocket 76 carried by a shaft 77. The bottom course of this chain as it passes from the sprocket 76 to the sprocket 74 is carried over an intermediate sprocket 78 connected in any suitable way to rotate with a large sprocket 79. This sprocket is driven by a chain 80 which is in turn driven by a sprocket 81 secured to the previously mentioned shaft 19. It will be apparent that through the connections explained, the chain 75 will be continuously shifted in the direction indicated by the arrows (Fig. 3) by power derived from the shaft 19. The rotation thus imparted to the shaft 73, and in turn to the shaft 68, will be at a relatively slow speed due to the reduction between the pinion 17 and gear 18 and the further reduction between the sprocket 81 and the sprocket 79. Now, as the conveyor 63 advances, the cup carried by the pins approaching the inner end of the conveyor will be dropped into a V trough 82 carried by a portion of the frame. As best shown in Fig. 1, a wall of the trough is notched, as indicated at 83, to permit the pins to pass through as the cup is deposited in the trough.

After the cup has been placed in the trough, a plunger 84, which is directly in line with the opening in the cup, is shifted toward the left (Fig. 1) until it engages the closed bottom of the cup and forces the latter into the open jaws of that chuck which, at this time, happens to be aligned with the trough, as indicated in Fig. 8. For the purpose of shifting the plunger in this manner, it is carried by an arm 85 secured to a rod 86 parallel with the plunger. The rod 86 passes through and is supported by a tube 87 and is connected at the rear of the machine with suitable operating mechanism. A pair of collars 88

and 89 may be secured to a rod and a block 90 is slideable on the rod. The block is normally held, by means of a spring 91, against the collar 89. Pins 92, projecting from the sides of the block, are engaged by the forked extensions of a lever 93 pivoted at its lower end upon a pin 94 carried by a portion of the machine frame. Intermediate its ends the lever 93 is provided with an elongated slot 95. A block 96, carried by a disc 97, cooperates with the slot so that upon rotation of the disc the lever will be rocked about its pivot. It will be understood that the block 96 is pivotally carried by the disc and its position on the disc may be made adjustable, if desired, so as to vary the stroke of the lever. For this purpose the pivot of the block may be shifted to any suitable position along a diameter of the disc.

For the purpose of rotating the disc 97, it is secured to a shaft 98 having a bevel gear 99 secured at its opposite end. A bevel pinion 100, meshing with the gear 99, is secured to a shaft 101, which also has secured thereto a sprocket 102. This sprocket is connected by means of a chain 103 with a sprocket 104 secured to the shaft 14 that receives power from the pulley 12. It will be apparent that through the connections indicated the lever 93 will be reciprocated once upon each rotation of the disc 97. The movement thus imparted to the rod 86 will be somewhat faster, at its maximum, as it is shifted toward the right in Fig. 2 than when it is shifted toward the left. This is for the reason that the lever arm through which the block 96 is acting in shifting the rod toward the right is somewhat shorter than that through which it acts in shifting the rod to the left. This is desirable inasmuch as the active movement of the plunger 84 toward the left should not be made too rapid at any time. The spring 91 enables a yielding pressure to be exerted by the plunger against the bottom of the cup toward the end of the movement of the plunger toward the left. This spring may, if desired, be made of sufficient length to prevent jamming of the parts in the event that the free movement of the plunger toward the left is interfered with. As the cup is forced between the jaws of the chuck upon the movement of the plunger toward the left, the spring-pressed elements 58 will yield slightly and when the cup is properly located, they will lightly grip its outer surface. As the plunger is now withdrawn from the cup, the corners 61 of the elements 58 will serve to retain the cup and prevent it from following the retractive movement of the plunger.

After the plunger 84 has been fully withdrawn from the cup, the head or disc 25 will be rotated through a quarter turn by means of the Geneva motion, previously explained. During the initial portion of this clockwise movement of the head (Fig. 5), the roller 51 will ride off of the high portion of the cam 56 and will permit the spring 53 to close the jaws of the chuck in the manner already described. As the rotation of the disc continues, the pulley wheel 35 on the spindle of this particular chuck will be carried into cooperation with a friction wheel 105 adapted to engage the surface of the pulley, within the groove. The disc 105 is secured to a shaft 106 carried by a frame 107 pivotally supported at 108 upon a portion of the main frame. A spring 109, bearing downwardly upon the frame 107 forwardly of its pivot, serves to yieldingly press the disc 105 into engagement with the pulley 35. The clockwise movement of the frame 107 (Fig. 2) may be suitably limited by means of a set screw 110. Any

suitable means, such as the handwheel shown, may be provided to vary the tension of the spring 109. A clutch 111 serves to couple the shaft 106 with a shaft 112 carrying a sprocket wheel 113. This sprocket is connected by a chain 114 with a wheel 115 secured to the drive shaft 14. Through the connections explained, the shaft 106 and friction wheel 105 will be rotated at a suitable speed. This in turn will serve to rotate the particular chuck which happens to be in the uppermost position on the head at any given time. The speed of rotation will be sufficient to permit the cutting operation, which will be presently explained, to be carried out under the appropriate conditions.

This leads us now to the operation of a cutter 116, which is adapted to be introduced an appropriate distance into the cup and then rocked downwardly into engagement with the interior surface of the cup. This is at a time when the cup is being rotated to carry its wall at a cutting speed so that the end of the cup will be trimmed off. For the purpose of imparting the necessary movements to the cutter, it is secured by a pair of set screws 117 within a sliding carriage 118. This carriage is slideable along ways 119 secured to, or integral with, a frame 120 pivoted by means of a pin 121 upon a portion of the main frame. The carriage is provided with a forked portion 122 with which cooperates a block 123 pivotally carried by a pair of arms 124. These arms are carried by a stud or shaft 125 mounted in the main frame and having secured at its outer end an arm 126. The latter in turn is connected by a link 127 with an arm 128 secured to a rock shaft 129. For the purpose of rocking this shaft, there is secured thereto an arm 130 to which is connected a link 131. The lower end of this link is provided with an elongated opening 132 surrounding the shaft 19. A roller 134, rotatably mounted upon the lower end of the link, cooperates with a cam 135 secured to the shaft 19. The roller is held against the cam by means of a pair of springs 136 connected to an arm 137 secured to the shaft 129. As will be seen best in Fig. 4, the springs 136 tend to lift the link 131 and hold the roller against the cam. It will be recalled that the shaft 19 is continuously rotated by the gearing 17, 18 which connects it with the drive shaft 14. It will be apparent that as the cam 135 rotates in the direction indicated by the arrow, the roller 134 will eventually drop from the high point of the cam so that under the action of springs 136, the shaft 129 will be rocked counter-clockwise (Fig. 4). This will cause the carriage 118 to be retracted, i. e., shifted toward the right in Fig. 9. As the rotation of the cam continues, the link 131 will be positively drawn downwardly against the action of springs 136 and the cutter 116 will be shifted into the open end of a cup. The length of the link 131 may be varied slightly so as to vary the extreme positions of the cutter carriage. By suitable adjustment of the link, the length of the cup remaining after the end has been removed may be varied to suit the particular requirements.

A somewhat similar mechanism is provided for rocking the frame 120 during the cutting operation. There is secured to the shaft 121 an arm 138 connected by a link 139 with an arm 140 secured to a shaft 141. Also secured to this shaft is an arm 142, to which is connected a link 143. The lower end of this link is provided with

an elongated opening 144, which receives the shaft 19. A roller 145, carried by the end of the link cooperates, with a cam 146 to control the movements of the link 143. The springs 136 also tend to lift the link 143 to maintain the roller 145 in engagement with the cam 146. For this purpose the springs 136 are connected with an arm 147 secured to the shaft 141. The arrangement is such that the cutter 116 will be rocked 10 downwardly from the position indicated in Fig. 9 to the position indicated in Fig. 10 by means of the positive action of the cam 146 with the carriage 118 in its left-hand position. Upon the completion of the cutting operation, the carriage 15 may be retracted and the frame 120 may be subsequently, or simultaneously, returned to its Fig. 9 position.

There are various advantages of the particular method of trimming the end of the cup provided 20 in this machine. It will be found, in the first place, that the outward pressure against the inner wall of the cup will produce no distortion whereas an inward pressure against the outer wall might very readily result in deformation of 25 the contour of the cup. This would not only spoil the article but would interfere with the cutting operation. Another feature to be observed is that the cutter is provided with two cutting edges. The material of the tube is first cut through by 30 means of the point 148 of the cutter and this is followed by the action of the edge 149, which serves to remove any burr that might be left by the point. Another advantage of the cutting operation provided in this machine is the easy 35 disposal of the trimmed ends of the cups. As the carriage 118 is retracted from the position shown in Fig. 10, the end of the cup will drop from the end of the cutter into any suitable receptacle or onto a chute, which may serve to discharge the 40 waste material to one side of the machine. Other advantages will be apparent from a careful consideration of the construction.

In order to insure the removal of the trimmed tips from the cutter 116, in the event they do not 45 slide off by gravity, a striker bar 116a is provided just above the cutter. It will be apparent that as the cutter is elevated toward its Fig. 9 position and is retracted, the striker bar will sweep any remaining trimmed end from the cutter. 50 The bar may be adjustably attached to the frame of the machine by screws 116b.

Upon completion of the trimming operation, the chuck carrying the trimmed cup will be shifted again by the Geneva movement out of the 55 position at the top of Figure 5 into the position at the right of this figure. As the chuck approaches the new position, the roller 51 will ride out upon the high part of the cam 56 and through 60 the rocking of the arm 46 will cause the jaws 58 of the chuck to be spread apart. The cup will, however, still be lightly retained by the plunger elements 58. In this position of the chuck its spindle will be directly aligned with a connection 150 at the end of an air discharge line. The end 65 151 of the detachable portion 32 of the spindle is provided with a beveled or sloping edge adapted to cooperate with a similar formation, shown in dotted lines in Figure 7, at the mouth 70 of the connection 150. The latter, as will be understood, may be arranged to yield slightly as the spindle is carried into position and it may then be held yieldingly against the seat 151. Air may be conveyed to the connection 150 from any 75 suitable source by means of a line 152. If de-

sired the air may be discharged continuously through this line or, if preferred, a valve may be provided to control the intermittent discharge of air at the appropriate time. Such a valve may be operated by any suitable portion of the operating mechanism of the machine and its operation may be so timed as to discharge a blast of air after the parts 150 and 151 have been brought into proper alignment. The air so discharged will pass through the spindle and be directed 10 against the bottom of the cup, which will thus be blown from the chuck into any suitable receptacle or to a conveyor conveniently located for the purpose.

Upon the next quarter turn of the head or 15 disc 25 the chuck from which the cup has just been removed will be shifted into the lower position (Fig. 5) where it remains entirely idle. In the meantime the chuck which was in the lower, idle position will have been shifted to the position at the left of Fig. 5, where it will receive a cup from the trough 82, in the manner explained. Thus, upon each cycle of the machine, while the head 25 is held stationary, a cup will be entered in the chuck at the left while the 25 upper chuck is rotated and the cutter is shifted in relation to the cup to trim the latter, and the chuck at the right will have its finished cup discharged by the air. It will be understood that the gearing from the power source to all of the 30 operating parts of the machine will be suitably timed to perform the various functions in the manner indicated.

In order that the machine may be adapted for the trimming of cups of different diameters, provision is made for the adjustment of the trough 82. This trough is carried by a table 153 which may be lifted or lowered, as desired, by the turning of a handwheel 154. This handwheel has threaded engagement with a spindle 155 which is secured to the table 153 at its upper end and is adapted to shift the table as the spindle is moved longitudinally by the handwheel. It will be apparent that in this way the table will either be raised or lowered, depending upon the direction of rotation of the handwheel. A spring 156 may be provided between the table and a portion of the fixed frame for the purpose of taking up the play in the parts and for frictionally locking the handwheel against accidental rotation. The 50 shaft 68 is also carried by the adjustable table so that the lower end of the delivery conveyor will be shifted upon the adjustment of the trough. It will be apparent that when the larger cups are to be trimmed, the table 153 will be 55 lowered to the point where the trough will hold a cup with its axis properly aligned with the jaws of the chuck. In adapting the machine to act upon cups of larger diameter, it will be necessary, of course, to replace the chucks by similar structures capable of retaining the larger cups.

The operation of the machine has been described so fully in conjunction with the detailed description of the various portions of the machine that a summary of operation is believed 65 to be unnecessary. It may simply be mentioned by way of summary that the cups or similar articles to be trimmed are successively fed by the conveyor 63 into the trough 82. For this they are fed by the plunger 84 between the open jaws 70 of that one of the chucks which at this moment happens to be at the left in Figures 3 and 5. At the same time the upper chuck will be rotated and the cutter 116 will be moved inwardly and 75 rocked downwardly, to trim off the end of the 75

cup then carried by the upper chuck, and will be subsequently retracted. In the retraction of the cutter the trimmed end will be dropped and conveniently disposed of. At the same time the cup 5 carried by the right-hand chuck, whose jaws are then open, will be blown from the machine by a blast of air delivered through the line 152. When these three operations, which are simultaneously conducted, are completed the head 25 10 will be rotated a quarter turn and the same operations will be repeated. It will be understood that the timing of the parts is such that upon each step of movement of head 25 the plunger 84 will be reciprocated once, the cutter 15 carriage will be reciprocated and rocked once, and the upper chuck will be rotated sufficiently to effect the trimming operation. Furthermore the conveyor 63 will move at the appropriate speed and will be so timed as to drop a new cup into 20 the trough 82 each time the plunger 84 is fully retracted. While a machine embodying the features of the invention has been described in considerable detail, and a preferred method of operation has been set forth, it will be understood 25 that these are merely for the purpose of clearly illustrating and pointing out the invention and that numerous changes in the form and arrangement of the parts and in the particular mode of 30 operation may be made without departing from the general spirit and scope of the invention.

What I claim is:

1. In a machine of the class described an intermittently rotatable head, a plurality of work holding means on said head constructed and arranged to retain hollow articles, a reciprocatory plunger aligned with one of said holding means in each position of the head and adapted to entering a hollow article and engage the bottom thereof to force the same into said holding means, means for rotating another of said holding means in each position of the head, means for discharging an article from another of said holding means in each position of the head, and common operating means for imparting step by step movement to the head, reciprocating said plunger, and rotating said second mentioned holding means, said plunger being given a continuous reciprocatory movement.

2. In a machine of the class described an intermittently rotatable head, a plurality of chucks rotatably mounted on said head, means effective upon movement of said head for opening the jaws of the chucks in certain positions and closing the jaws in another position assumed upon movements of said head, means for automatically introducing and discharging articles with relation to the chucks when open, gripping means yieldingly mounted on the chuck jaws for retaining the articles when the chucks are open, means for rotating the chucks when in said other position, and means for shifting a tool into cooperative relation with an article held by the rotating chuck.

3. In a machine of the class described an intermittently rotatable head, a plurality of chucks rotatably mounted on said head, a stationary cam, means on said chucks cooperating with said cam to control the opening and closing of the jaws of the chucks upon movements of the head, means for automatically introducing and removing articles with relation to the chucks when open, gripping means yieldingly mounted on the chuck jaws for retaining the articles in the chucks when the latter are open, and means for 75 rotating the chucks when closed.

4. In a machine of the class described, a work supporting chuck, a hollow spindle rotatably supporting said chuck, means for rotating said chuck, a cam means for controlling the opening and closing of the jaws of said chuck, a plunger 5 for introducing an article into the chuck when open, means yieldingly carried by the chuck jaws for lightly retaining the article when the chuck is open, and means for discharging a fluid medium through said spindle to remove an article 10 from the chuck when the chuck is open.

5. In a machine of the class described a rotatable spindle, a plurality of chuck jaws pivoted upon said spindle, means for rotating said jaws, means for opening and closing said jaws, means 15 for inserting an article into and removing an article from said jaws when open, and yielding means in said jaws for lightly retaining an article while the jaws are open.

6. In a machine of the class described a rotatable spindle, a plurality of chuck jaws pivoted upon said spindle, means for rotating said jaws, a reciprocatory plunger for inserting an article between said jaws, means for directing a fluid between said jaws to remove the article, 25 and yielding means in said jaws for lightly retaining an article while the jaws are open.

7. In a machine of the class described means for supporting a hollow tubular member, means for rotating said supporting means, a tool carriage, means for sliding said carriage to introduce a cutting tool into said member, and means for rocking the carriage bodily to effect cutting engagement between the tool and member.

8. In a machine of the class described means 35 for supporting a hollow tubular member, a tiltable frame, a tool carriage slidable on said frame, and means for sliding said carriage and tilting said frame to carry a tool into cutting engagement with said member.

9. In a machine of the class described means for supporting a hollow tubular member, means for rotating said supporting means, a tool holder, means for shifting said tool holder to carry a tool into said member, and separate means for 45 moving the cutting portion of the tool transversely across the rotating tubular member.

10. In a machine of the class described a rotatable head, a plurality of work supporting means on said head, a conveyor for delivering 50 thin walled tubular work pieces in line with said supporting means when in one position, means on said conveyor for retaining said pieces in spaced relation, a reciprocatory feed member, means for imparting step by step movement to said head 55 to carry said supporting means successively into line with said member, and means for reciprocating said member to transfer the work pieces carried by said conveyor to said supporting means.

11. In a machine of the class described a rotatable head, a plurality of work holders on said head, a work piece receiving trough, means for adjusting the position of said trough independently of said conveyor, a conveyor for successively delivering work pieces into said trough, means 65 for intermittently rotating said head step by step to carry said work holders successively adjacent said trough, and means for transferring work pieces from said trough to said work holders successively.

12. In a machine of the class described means for supporting and rotating a hollow tubular member at a cutting speed, means for supporting an elongated cutting tool, means for quickly sliding said supporting means to carry the cutter 75

into the interior of the tube, and separate means for more slowly moving the point of the cutter outwardly through the wall of the tube.

13. In a machine of the class described rotatable means for supporting a hollow tubular article, means for rotating said supporting means, a tool holder, means for retaining a cutter thereon, cam means for shifting said holder to carry the cutter into said article and separate cam means for shifting said cutter outwardly through the wall of the article.

14. In a machine of the class described rotatable means for supporting a hollow tubular article, means for rotating said supporting means, a tool holder, means for retaining a cutter thereon, a pair of cams, means controlled by one of said cams for carrying the cutter into said article, means controlled by the other of said cams for shifting the cutter outwardly through the wall of the article, and common spring means for urging portions of said cam controlled means against said cams.

15. In a machine of the class described a rotatable chuck, means for carrying hollow articles to a point adjacent said chuck, a reciprocatory member for transferring articles from said point to said chuck, and means for operating said member comprising a continuously rocking element and means for operating the same more quickly in one direction than the other.

16. In a machine of the class described a rotatable chuck, means for carrying hollow articles

to a point adjacent said chuck, a reciprocatory member for transferring articles from said point to said chuck, and means for operating said member comprising a slotted lever and a rotatable disk having an element cooperating with the slot in said lever.

17. A machine for trimming hollow, thin-walled metal tubes which comprises a support arranged to retain a tube with its end to be trimmed extending freely therefrom, means for rotating said support to carry the tube at a cutting speed, means for supporting a cutting tool, means for moving said tool supporting means to carry the cutting point of the tool quickly into the tube through a predetermined distance out of cutting engagement with the tube and then more slowly moving the cutting point of the tool outwardly through the wall of the tube.

18. A machine for trimming hollow, thin-walled metal tubes which comprises a support arranged to retain a tube with its end to be trimmed extending freely therefrom, means for rotating said support to carry the tube at a cutting speed, means for supporting a cutting tool, means for moving said tool supporting means to carry the cutting point of the tool quickly into the tube through a predetermined distance out of cutting engagement with the tube and then more slowly rocking the cutting point of the tool outwardly through the wall of the tube.

JOHN H. FRIDÉN.
